A. MEFFERT

BATHING ATTIRE

Filed April 15, 1922

Inventor

Alexander Meffert.

By his Attorney
Thos. J. Daffel.

UNITED STATES PATENT OFFICE.

ALEXANDER MEFFERT, OF NEW YORK, N. Y.

BATHING ATTIRE.

Application filed April 15, 1922. Serial No. 553,127.

To all whom it may concern:

Be it known that I, ALEXANDER MEFFERT, a citizen of the United States, residing at New York city, in the county of New York and State of New York, have invented certain new and useful Improvements in Bathing Attire, of which the following is a specification, reference being had therein to the accompanying drawing.

10 My invention relates to improvements in bathing attire, and more particularly has reference to and is illustrated in the accompanying drawing in its application to a multi-piece or combination suit adapted for 15 use by non-swimmers as a safeguard against drowning.

Referring to said drawing, 1 indicates the shirt of the suit, and 2 the belt or life saving attachment, and 3 a jockstrap or trunks. 20 The belt 2 is substantially flat being provided with the usual ribs 4, and valve 5 for admitting air, the ends being provided with suitable eyelets or hooks 6 for lacing, as indicated at 7. The upper and lower margins 8—9 of the belt are provided with eyelets or other suitable fastening means such as 10 by which the shirt 1 and jockstrap or trunks 3 may be suitably attached.

It has been customary in teaching swimming to use a substantially flat inflated belt somewhat similar to the belt 2, but the belt is loosely applied and floats up under the arm pits of the novice causing chafing and annoyance, whereas by securing thereto a 35 pair of trunks, or a jockstrap, such as illustrated, the upward shifting of the life belt is prevented and by the addition of the shirt 1, the belt can be applied fairly loosely if desired, and yet will not slip down 40 when out of the water. Of course it will be readily understood that the belt and jockstrap may be used beneath a bathing suit or it may be used in combination with the shirt and trunks of a bathing suit as shown, 45 or the belt and trunk combination may be

used beneath the bathing shirt alone. This form of life belt will give ample buoyancy and at the same time remains close to the body without presenting any very noticeable obstruction when worn beneath a shirt, or 50 may be finished in suitable color and configuration so as to render it not objectionable when exposed. With a suit of this kind, it is practically impossible to drown as the body will normally remain upright, and at 55 the same time it affords facility for every possible movement in swimming, and is no practical inconvenience when out of the water.

Of course it will be understood that various modifications may be made in the construction and arrangement of parts without departing from the spirit of the invention as claimed.

I claim:

1. In combination with a substantially flat inflatable belt having upper and lower circumferential marginal flanges, a garment adapted to be secured to said lower flange and means in combination with the top of 70 said garment and said lower flange for detachably securing the same together, a shirt, and means in combination with the same and said upper flange for securing said shirt and said flange together.

2. In combination with a substantially flat inflatable belt having a circumferential marginal flange, a jockstrap adapted to be secured thereto, and means in combination with said flange and the top of said jockstrap for detachably securing the same together, a second circumferential marginal flange at the top of said belt, a shirt, and means in combination with said second flange and said shirt for detachably securing the same together.

In testimony whereof I hereunto affix my signature.

ALEXANDER MEFFERT.
